UNITED STATES PATENT OFFICE.

BENJAMIN F. WHEELER, OF MALDEN, MASSACHUSETTS.

SOLE-TRIMMING MACHINE FOR BOOTS AND SHOES.

SPECIFICATION forming part of Letters Patent No. 259,253, dated June 6, 1882.

Application filed December 27, 1881. (No model.)

To all whom it may concern:

Be it known that I, BENJAMIN F. WHEELER, of Malden, in the county of Middlesex and State of Massachusetts, have invented certain new and useful Improvements in Sole-Trimming Machines for Boots and Shoes, of which the following, taken in connection with the accompanying drawings, is a specification.

My invention relates to that class of sole-edge-trimming machines in which the cutting-tool commonly called an "edge-plane" is used; and it consists in certain novel combinations and arrangements of devices for controlling the position of the boot or shoe placed upon the jack and properly presenting the different parts of the sole-edge to the action of the cutting-knife, which will be best understood by reference to the description of the drawings and to the claims to be hereinafter given.

Figure 1 of the drawings is a plan of a machine embodying my invention. Fig. 2 is a side elevation of the same. Fig. 3 is a sectional elevation of the upper portion of the machine, drawn to an enlarged scale, the cutting-plane being on line $x-x$ on Figs. 1 and 2. Fig. 4 is a vertical transverse section on line $y-y$ on Figs. 1 and 2, looking toward the rear end of the machine. Fig. 5 is an inverted plan, a portion of the head of the machine, and the jack-carrying carriage mounted thereon; and Fig. 6 is a detail of the cam and lever for operating the jack-carriage.

A is a column provided with a broad base, A', and having secured to its upper end the frame B, which extends horizontally to the rear of said column and upward and forward upon the opposite side of said column, as shown in Fig. 1.

C is a worm-shaft mounted in bearings in the rear portion of the frame B, and having mounted thereon the two loose pulleys D and D', each having formed in its inner face a conical recess, a, to receive one of the conical ends of the frictional clutch b, as shown in Fig. 1. The clutch b has formed in its periphery the circumferential groove b', with which pins c c, set in the forked arm of the three-armed lever E, engage, so that by a vibratory movement of said lever said clutch may be moved endwise on the shaft C, while at the

same time it may revolve therewith, being impelled thereto by means of a keyway and spline in a well-known manner. The two horizontal arms d and d' of the lever E, are respectively connected by the rods F and F' to the rear ends of the treadle-levers G and G', pivoted to the base of the column A, as shown in Figs. 1 and 2. The worm e upon the shaft C meshes into and imparts motion to the worm-wheel H, mounted upon the shaft I, which has its bearings in the frame B, and carries upon one end the spur-gear wheel J and upon its opposite end the cam K. The gear-wheel J meshes into and imparts motion to the rack L, fitted to slide in a suitable bearing formed for the purpose in the frame B, and carrying upon its upper side the stand M, in the upper end of which is formed a socket to receive the ball f, which is perforated to receive the rear end of the rod g, which is firmly secured to said ball by the set-screw h, as shown in Fig. 7. The front end of the rod g is bent, as shown in Fig. 1, and has formed therein an eye or hole to receive a hook, i, attached to the stock of the edge-plane N in a well-known manner.

O is a carriage fitted to move horizontally on slides j j on the under side of the front portion of the frame B, and connected by the rod P to the upper end of the lever Q, pivoted at k to the frame B, and carrying at its lower end the stud l, which fits into and is acted upon by the path m of the cam K, as best shown in Fig. 6. The carriage O has fitted to suitable bearings formed therein the shaft S, to one end of which is firmly clamped by the nut n the jack T, upon which the boot or shoe to be trimmed is placed, as shown in Figs. 1 and 2. The shaft S has firmly secured thereon the spirally-grooved sleeve or pulley S', around which is wound the cord U, made preferably of rawhide, one end of which is firmly secured to the frame B at o, and the opposite end of which has securely attached thereto the metal shank U', which is adjustably connected to the frame B at p by means of a screw-thread cut upon said shank and the nut q, as shown in Fig. 5, whereby said cord can be drawn taut, and any slack caused by the stretching of said cord may be taken up. It will be seen that a movement of the carriage O along its

slides *j* will cause a partial rotation of the shaft *S* in one or the other direction, according as the carriage is moved toward the rear or the front of the machine.

5 The operation of my invention is as follows: The several parts of the machine being in the position shown in the drawings, and the boot or shoe being placed upon the jack, the operator takes the edge-plane *N* by the handle, as shown in Fig. 2, and holds it in the position shown upon the edge of the sole, and then places his foot upon the treadle *G* to depress it, which causes the friction-clutch *b* to engage with the pulley *D*, which is revolved by means 15 of an open belt (not shown) leading therefrom to a pulley upon a suitable counter or driving shaft overhead, (but not shown,) thereby causing the shafts *C* and *I* to revolve in the directions indicated by the arrows *r* and *s*, respectively. The revolution of the shaft *I* and the gear *J* in the direction of the arrow *s* causes the rack *L*, stand *M*, rod *g*, and edge-plane *N* to be moved toward the rear of the machine, the cutter being steadied and guided by the 20 hand of the operator till the edge of the cutter arrives at a point on the shoe-sole edge about opposite the center of the curve of the toe, as indicated by the dotted line *x x*, at which time the point *t* in the path of the cam 25 *K* will have arrived on a line with the center of the stud set in the lower end of the lever *Q*, when the continuation of the revolution of said shaft *I* will cause the lever *Q* to be vibrated about its fulcrum, so as to move the carriage 30 *O* toward the rear of the machine while that portion of the path of the cam *K* between the points *t* and *u* is passing the stud *l* in the lower end of the lever *Q*, which rearward movement of the carriage *O* causes the shaft *S* to be 35 turned about its axis to the extent of one-half of a revolution, the jack *T* and the boot or shoe mounted thereon revolving therewith. When the jack and boot or shoe has made one-half of a revolution the motion of the carriage *O* ceases and the shoe is held stationary, while the motion of the knife or cutter continues 40 along the edge of the sole till it reaches the rear portion of the shank of the boot or shoe, when the operator lifts the cutter away from 45 the sole, and at the same time removes his foot from the treadle *G*, when the clutch *b* is released from contact with the pulley *D* by the action of a spring or weight, (not shown,) so arranged and operated as to tend to hold said 50 clutch in a position equidistant between the two pulleys *D* and *D'* in a well-known manner.

The edge-plane *N* when not required for use—as during the time of putting on and taking off the boot or shoe—is hung upon a wire or cord in a convenient position above the machine (but not shown) by means of the spring-hook *v*.

60 The jack *T* is of such a form and so secured to the shaft *S* that it revolves or vibrates about an axis coinciding with the axis of the shaft *S*, and with the center of curve of the rounded toe of the boot or shoe placed thereon; and

it will be obvious, upon careful consideration, that if the jack were revolved against the advancing movement of the edge plane or cutter without any rearward movement of the jack the speed of the cutter would be greater during the turning of the jack and while the toe of the boot or shoe is being trimmed than while the cutter is moving along the side of the sole-edge, which would be objectionable on account of the increased difficulty of controlling the cutter, and hence the necessity for employing the movable carriage *O*, the cam for operating which should be so formed as to move said carriage toward the rear during the turning of the last a distance just sufficient to compensate for the backward motion of the edge of the toe portion of the sole, due to the rotation of said shoe about an axis coinciding with the center of the curve of said toe.

When the stroke of the edge-plane is completed and the operator removes his foot from the treadle *G*, if he desires to trim another boot or shoe he places his foot upon the treadle *G'* and depresses it, which causes the clutch *b* to engage with the pulley *D'*, which is revolving in a direction opposite to that indicated by the arrow *r* and the edge-plane *N*, and the carriage *O* will be moved toward the front of the machine, and the shaft *S* and jack *T* will be revolved in the opposite direction till the parts assume the position shown in the drawings, when the operator removes his foot from the treadle *G'* and the jack will remain at rest 100 till the boot or shoe is removed and another one applied thereto.

What I claim as new, and desire to secure by Letters Patent of the United States, is—

1. The combination, in a sole-trimming machine, of the jack *T*, the carriage *O*, mounted and adapted to be reciprocated upon suitable slides, the spirally-grooved pulley *S'*, and the cord *U*, all constructed, arranged, and adapted to operate substantially as described.

2. In a sole-trimming machine, the combination of the reciprocating carriage *O*, the shaft *S*, the spirally-grooved pulley *S'*, the jack *T*, the cord *U*, the cam *K*, lever *Q*, and means of connecting the lever *Q* and the carriage *O*, substantially as and for the purposes described.

3. The combination of the movable carriage *O*, the spirally-grooved pulley *S'*, the cord *U*, wound around said pulley and firmly secured by one end to a fixed portion of the machine, and the threaded shank *U'*, secured to the opposite end of said cord and provided with the nut *q*, whereby the other end of said cord may be secured to a fixed portion of the frame and any slack therein may be taken up, substantially as described.

4. The combination, in a sole-trimming machine, of the rack *L*, the stand *M*, the ball *f*, the rod *g*, fitted to an opening through said ball so as to be adjusted therein, and the edge-plane *N*, connected to and adapted to be operated by said rod *g*, substantially as described.

5. The combination, in a sole-trimming ma-

chine, of an edge-plane, mechanism for imparting to said plane a reciprocating motion, a jack-carrying carriage mounted upon slides, mechanism for automatically imparting to said carriage an intermittent reciprocation in a right line, and mechanism for imparting to the jack a semi-rotation during each forward or backward stroke of said carriage, substantially as and for the purposes described.

Executed at Boston, Massachusetts, this 22d 10
day of December, A. D. 1881.
